US0D1038380S

(12) **United States Design Patent** (10) Patent No.: **US D1,038,380 S**
 DiLuzio et al. (45) Date of Patent: ** Aug. 6, 2024

(54) **AUTOINJECTOR**

- (71) Applicant: **Millennium Pharmaceuticals, Inc.**,
 Cambridge, MA (US)
- (72) Inventors: **Willow Ruth DiLuzio**, Gloucester, MA
 (US); **Nobel T. Truong**, Milford, MA
 (US); **Sarah Royalty Tredo**, Vernon
 Hills, IL (US); **Donald J. Rogers, Jr.**,
 Carmel, IN (US)
- (73) Assignee: **Millennium Pharmaceuticals, Inc.**,
 Cambridge, MA (US)
- (**) Term: **15 Years**
- (21) Appl. No.: **29/894,912**
- (22) Filed: **Jun. 15, 2023**

Related U.S. Application Data

- (62) Division of application No. 29/706,511, filed on Sep.
 20, 2019, now Pat. No. Des. 1,010,817, which is a
 division of application No. 29/557,806, filed on Mar.
 11, 2016, now Pat. No. Des. 866,757.

CLAIM

The ornamental design for an autoinjector, as shown and described.

DESCRIPTION

The file of this patent contains at least one drawing executed in color. Copies of this patent with color drawing(s) will be provided by the Office upon request and payment of the necessary fee.

FIG. 1 is a front perspective view illustrating a first exemplary embodiment of our ornamental design for an autoinjector with a purple removable cap.

FIG. 2 is a front elevational view of the first exemplary embodiment of our ornamental design for an autoinjector of FIG. 1, the rear elevational view being a mirror image thereof.

FIG. 3 is a right side elevational view of the first exemplary embodiment of our ornamental design for an autoinjector of FIG. 1, the left side elevational view being a mirror image thereof.

FIG. 4 is a bottom plan view of the first exemplary embodiment of our ornamental design for an autoinjector of FIG. 1. FIG. 5 is a top plan view of the first exemplary embodiment of our ornamental design for an autoinjector of FIG. 1.

FIG. 6 is a front perspective view illustrating a second exemplary embodiment of our ornamental design for an autoinjector with a purple removable cap.

FIG. 7 is a front elevational view of the second exemplary embodiment of our ornamental design for an autoinjector of FIG. 6, the rear elevational view being a mirror image thereof.

FIG. 8 is a right side elevational view of the second exemplary embodiment of our ornamental design for an autoinjector of FIG. 6, the left side elevational view being a mirror image thereof.

FIG. 9 is a bottom plan view of the second exemplary embodiment of our ornamental design for an autoinjector of FIG. 6.

FIG. 10 is a top plan view of the second exemplary embodiment of our ornamental design for an autoinjector of FIG. 6. FIG. 11 is a front perspective view illustrating a third exemplary embodiment of our ornamental design for an autoinjector with a removable cap.

FIG. 12 is a front elevational view of the third exemplary embodiment of our ornamental design for an autoinjector of FIG. 11, the rear elevational view being a mirror image thereof.

FIG. 13 is a right side elevational view of the third exemplary embodiment of our ornamental design for an autoinjector of FIG. 11, the left side elevational view being a mirror image thereof.

FIG. 14 is a bottom plan view of the third exemplary embodiment of our ornamental design for an autoinjector of FIG. 11.

FIG. 15 is a top plan view of the third exemplary embodiment of our ornamental design for an autoinjector of FIG. 11.

FIG. 16 is a front perspective view illustrating a fourth exemplary embodiment of our ornamental design for an autoinjector with a removable cap.

FIG. 17 is a front elevational view of the fourth exemplary embodiment of our ornamental design for an autoinjector of FIG. 16, the rear elevational view being a mirror image thereof.

FIG. 18 is a right side elevational view of the fourth exemplary embodiment of our ornamental design for an autoinjector of FIG. 16, the left side elevational view being a mirror image thereof.

FIG. 19 is a bottom plan view of the fourth exemplary embodiment of our ornamental design for an autoinjector of FIG. 16; and,

FIG. 20 is a top plan view of the fourth exemplary embodiment of our ornamental design for an autoinjector of FIG. 16.

The broken lines depict portions of the article that form no part of the claimed design.
